Primary Examiner — Karen S Acker(74) *Attorney, Agent, or Firm* — Steven M. Hoffberg;
Ostrolenk Faber LLP(57) **CLAIM**

The ornamental design for a wallpaper product with a surface pattern, shown and described.

DESCRIPTION

The sole FIGURE is a top view of a wallpaper product having a surface pattern.

The peripheral intermittent broken lines in the drawing form the boundaries of the claim and form no part thereof. The dotted lines within the drawing are part of the claim.
